By *J. M. Moore*,
Attorney.

UNITED STATES PATENT OFFICE.

ARTHUR BEARGEON, OF COMPTON, CALIFORNIA.

GRAVEL-SEPARATOR.

SPECIFICATION forming part of Letters Patent No. 663,212, dated December 4, 1900.

Application filed March 27, 1900. Serial No. 10,315. (No model.)

To all whom it may concern:

Be it known that I, ARTHUR BEARGEON, a citizen of the United States, residing at Compton, in the county of Los Angeles and State 5 of California, have invented certain new and useful Improvements in Sand and Gravel Separators, of which the following is a specification, reference being had therein to the accompanying drawings.

10 This invention relates to improvements in car-loaders provided with screens for gravel and the like; and the novelty resides in the peculiar construction and combination of parts, all as more fully hereinafter described, 15 shown in the drawings, and then particularly pointed out in the claims.

The invention is clearly illustrated in the accompanying drawings, which, with the letters of reference marked thereon, form a part 20 of this specification, and in which—

Figure 1 represents a side elevation of my improved screen in position for use upon a flat-top car. Fig. 2 is a top plan view, and Fig. 3 is a detail view, of one of the screen 25 operating and adjusting devices.

Like letters of reference indicate like parts throughout the several views.

In the drawings, A designates a flat-top car of known construction.

30 B is a plow having a substantially V-shaped head portion provided with a clevis D for the attachment of a cable for drawing the plow over the top of the car. C is a rectangular frame to which the head or front portion is secured. This frame may be strengthened by brace-bars, as shown. This plow and frame are connected with a rectangular frame D', from the front and rear corners of which rise the standards E, formed at their upper ends 35 with journals or bearings F, in which are mounted the upper bars G of the screens G', one of which is secured upon each side of the device, as shown. Depending from the bars G are the rods g, secured thereto in any suitable manner. The bars G are each extended rearward and downward, as seen best in Fig. 45 1, to form crank-arms J, to each of which is connected, in any suitable manner, one end of a chain K, each chain being wound upon a

rod L, mounted in the frame D', and in extensions c of the frame C, as shown. Fast on each of said rods L is a disk M, having a series of openings N, any one of which is adapted to be engaged by a dog or detent O, pivoted on the extension c of the frame C, 55 the purpose of the same being to hold the screens at any desired adjustment, according to the size of gravel to be screened. When the rods L are turned, the chains move the crank-arms J, and thereby the lower ends of rods g of the screens either toward or away 60 from the frame.

In operation the flat-cars forming the train are all in line after the manner of a continuous platform with the sand and gravel upon 65 the top of the cars. The nose of the plow rests flush with the top rear end of one of the cars and into the material, and when the plow is drawn along it pushes the gravel and sand outward, and the sand and smaller 70 gravel—i.e., that capable of being pushed or of passing between the lower ends of the screen-rods and the sides of the platform—fall together along with the sand and gravel which passes between the rods of the screens and 75 forms a pile or row of mixed sand and small gravel on each side of the car, while the larger gravel (not passing through between the screen-rods or between the lower ends of the rods and the sides of the platform) is pushed 80 ahead on the platform where, as it works its way to the side of the platform and in front of the plow-frame, it drops off the platform ahead of and in line with the line of mixed sand and gravel alongside of the track and 85 can be removed in any suitable manner.

I claim—

1. In a gravel-separator, the combination of a frame, a plow arranged therein, and screens arranged on each side of said plow 90 and connected with said frame.

2. A car-unloader, consisting of a plow, an outer frame connected therewith, screens connected with said frame on opposite sides of said plow, and mechanism for adjusting 95 said screens, substantially as described.

3. In a gravel-separator, the combination with a car, of a frame resting on the top

thereof, a plow carried by said frame, standards rising from the frame on each side of the plow, and screens connected with said standards.

5 4. In a gravel-separator, the combination with a car, of a plow resting flat upon the same and adapted to be drawn over the car, screens arranged on each side of the plow

and connected therewith, and mechanism for adjusting the screens.

In testimony whereof I affix my signature in presence of two witnesses.

ARTHUR BEARGEON.
